UNITED STATES PATENT OFFICE.

MORRIS POLNOROFF, OF PHILADELPHIA, PENNSYLVANIA, ASSIGNOR OF ONE-HALF
TO MORRIS ABEL, OF PHILADELPHIA, PENNSYLVANIA.

RADIATOR.

1,400,978.

Specification of Letters Patent. Patented Dec. 20, 1921.

Application filed February 14, 1921. Serial No. 444,787.

To all whom it may concern:

Be it known that I, MORRIS POLNOROFF, a citizen of the United States, residing at Philadelphia, in the county of Philadelphia and State of Pennsylvania, have invented 5 new and useful Improvements in Radiators, of which the following is a specification.

This invention relates to radiators such as are used on automobiles for the purpose 10 of cooling the water passing through the circulatory system of the engine, and has for its object the provision of a radiator in which the cooling tubes are formed in groups, any group being removable without 15 in any way affecting the other group, the great advantage of the device being that in case of damage to the radiator, the damaged section or group may be removed and replaced without in any way affecting the 20 others.

An important and most specific object is the provision of a radiator of this character in which there is provided a series of vertically arranged tubes disposed between the 25 upper and lower tanks of the radiator, the tubes communicating with the interiors of pan like heads which have a dove-tailed connection with the upper and lower tanks.

An additional object is the provision of a 30 radiator of this character which will be simple and inexpensive in construction, easy in assembling, highly efficient in use, durable in service and a general improvement in the art.

With the above and other objects and advantages in view, the invention consists in the details of construction to be hereinafter more fully described and claimed, and illustrated in the accompanying drawings, in 40 which:—

Figure 1 is a front elevation of a radiator constructed in accordance with my invention.

Fig. 2 is a side elevation thereof with 45 portions broken away and in section.

Fig. 3 is a perspective view of one of the pan like heads showing one side thereof.

Fig. 4 is a perspective view showing the reverse side thereof, and

Fig. 5 is a fragmentary perspective view 50 of one end of the bottom closure plate of the upper tank or the top closure plate of the lower tank.

Referring more particularly to the drawings I have shown my radiator as comprising

ing upper and lower tanks 10 and 11 respectively, the former of which is provided with the usual filling neck 12. The bottom of the upper tank 10 and the top of the lower tank 11 are closed by plates 13 and 14 respectively which are formed on their confronting faces with dove-tailed grooves 15 which are similar. The upper and lower tanks are connected by side members 16 constituting a species of frame which are preferably webbed as shown at 17 for the purpose of providing great strength.

The numeral 18 designates a series of vertically disposed cooling tubes which extend between the upper and lower tanks and these 70 tubes are arranged in groups or sections as clearly shown in Fig. 1. At its upper and lower ends each group of tubes carries and communicates with pan shaped heads 19 clearly disclosed in Figs. 3 and 4 of the 75 drawings. These pan heads are formed with dove-tailed projections 20 slidably fitted within the dove-tailed grooves 15. Likewise associated with and extending through one end of the heads 19 are tubes 21 having 80 their ends within the heads beveled and cut-away as indicated at 22 and formed adjacent their outer ends with holes 23. These tubes 21 are disposable through holes formed in extensions 24 in the closure plates 13 and 85 14 and have their extremities threaded and provided with closure caps 25.

The extensions 24 on the plates 13 and 14 extend longitudinally of the plate and are formed with a plurality of spaced openings 90 26 which establish communication with the respective tanks as clearly shown in Figs. 2 and 5. Certain of the portions of the extensions 24 are formed with holes 27 for the passage of the tubes 21 as will be readily apparent.

In actual practice the various vertical tubes 18 may be provided with any suitable cooling portions, though in the present instance I have shown them as formed with 100 spirally arranged cooling ribs 28.

In the assembling of my radiator the various groups or sections of tubes are inserted by engaging the upper and lower pan like heads 19 within the corresponding 105 dove-tailed grooves 15 in the plates 13 and 14 respectively with the tubes 21 passing through the registering holes 27 in the extensions 24. The caps 25 are then screwed onto the threaded ends of the tubes 21 110

whereupon removal or accidental displacement of the pan heads and consequently the tube groups or sections will be prevented. Owing to the fact that the extensions 24 5 are hollow or provided with the opening 26 and owing to the provision of the holes 23 in the tubes 21 it will be seen that communication will be established between the upper and lower tanks of the radiator, through the 10 pan-like heads 19 and through the tubes 18 so that an effective circulation will be maintained.

From the foregoing and a study of the drawings it will be apparent that I have 15 thus provided a very simply constructed and consequently inexpensive radiator in which the tubes are arranged in sections, any of the sections being easily and quickly removable without disturbing any of the 20 other sections. It is thus to be observed that the radiator is particularly advantageous in cases of accident such as damage in a collision or in case of breaking inasmuch as the removal and replacement of one 25 group of tubes may be effected without interfering with the other group or section.

While I have shown and described the preferred embodiment of the invention, it is of course to be readily understood that I 30 reserve the right to make such changes in the form, construction and arrangement of parts as will not depart from the spirit of the invention or the scope of the subjoined claims.

35 Having thus described the invention I claim:

1. A radiator comprising upper and lower tanks, the upper and lower tanks being closed at their lower and upper surfaces respectively by means of plates formed with 40 hollow extensions communicating with the tanks, said plates being formed in their confronting faces with grooves, a series of vertically disposed tubes disposed between said 45 tanks, pan-like heads carried by and communicating with the upper and lower ends of said tubes and formed with extensions fitting within said grooves, extensions formed on said plates and provided with 50 openings communicating with the respective tanks, said last named extensions being pro-

vided in registration with said grooves with openings and tubes carried by said pan-like heads passing through said openings and carrying retaining caps. 55

2. A radiator comprising upper and lower tanks, plates forming closures for the lower and upper surfaces of said upper and lower tanks respectively, said plates being formed with dove-tailed grooves and being formed on their confronting faces with extensions formed hollow and communicating with the interiors of the tanks, a plurality of vertically disposed tubes arranged between said tanks, heads closing and communicating with the interiors of the tubes and dividing the same into groups, said heads being formed with dove-tailed tongue members fitting within said grooves, tubes carried by and communicating with the interiors of 70 said heads and passing through the hollow extensions on said plates, caps secured on the free ends of said tubes whereby to prevent dislocation of the heads, and said tubes being formed with holes communicating 75 with the interiors of said first named extensions. 85

3. A radiator comprising upper and lower tanks, plates forming closures for the lower and upper sides of said upper and lower tanks respectively, said plates being formed in their respective faces with dove-tailed grooves, a series of vertically disposed tubes arranged between said tanks, heads carried by and communicating with the upper and lower ends of said tubes, said heads being formed with dove-tailed extensions slidably engaged within said grooves, tubes carried by and communicating with the interiors of said heads, extensions on the plates provided with openings communicating with the tanks, said extensions being formed in registration with said grooves with holes, tubes carried by and communicating with said heads and passing through said holes, said tubes being formed with holes communicating with the interiors of the extensions, and caps screwed upon the free ends of said tubes whereby to prevent displacement of the groups of tubes. 95 100

In testimony whereof I affix my signature.
MORRIS POLNOROFF.
